UNITED STATES PATENT OFFICE.

HERMAN BRUEGER, OF JERSEY CITY, NEW JERSEY.

POCKET-BOOK.

SPECIFICATION forming part of Letters Patent No. 767,793, dated August 16, 1904.

Application filed March 7, 1904. Serial No. 196,930. (No model.)

To all whom it may concern:

Be it known that I, HERMAN BRUEGER, a citizen of the United States, residing at Jersey City, in the county of Hudson and State of New Jersey, have invented new and useful Improvements in Pocket-Books, of which the following is a specification.

This invention relates to pocket-books, porte-monnajies, and the like.

10 The object of my invention is to provide for applying and securing the tab, usually called the "tuck," to the flap of a pocket-book without the usual stitching and give a neater and more satisfactory finish to the connected parts.

The particular features of construction constituting my invention will be set forth in the claims.

I will now describe the details of construction by reference to the accompanying drawings, in which—

Figure 1 represents a perspective view of a pocket-book, showing the tuck applied to one of the flaps. Fig. 2 represents an inner face view, on enlarged scale, of a flap and tuck. Fig. 3 represents a vertical section of the same. Fig. 4 represents an inner face view of the parts in the course of construction.

30 The pocket-book A may be of the usual compound construction, with one of its covers or the back B provided with an interior pocket and having a flap C for closing the same. The tuck D has usually been made separate and secured by one or more transverse lines of stitches near its middle portion to the flap C; but this stitching is inconvenient and an objectionable expense. I have therefore devised a method and means for making the 40 tuck as a part of the flap and so constructing and connecting them as to avoid stitching them together and to save expense in construction. The flap C is made with an outer cover of leather or other suitable material and a lining or body portion of cardboard, paper, or other stiffening material c, having a central projecting tongue or tab c'. The edges f of the leather are turned over and secured by glue or other adhesive upon the body or

filling c. To the paper or other interior filling e in the tuck D is applied a reinforcing tip or covering of muslin h. The leather cover is then applied to the filling of the tuck, and at the rear end or thumb-piece d thereof the edges d' of the leather are turned over and glued onto the filling of paper or paper and muslin, and then a thin lining g is glued or cemented on the inner face of the part d of the tuck to give it a suitable finish. The tuck D is now glued at its forward half to the tongue portion c' of the flap, and the free edges d'', Fig. 4, are turned over and glued to the inner face of the tongue, as shown in Fig. 2. Before turning the edges d'' of the tuck over and securing them by glue or other adhesive 60 on the tongue c' a strip of muslin or other fabric h' is preferably passed over the filling e of the tuck and then turned over, crossed, and glued on the filling c at the junction of the tuck and flap, as shown in Fig. 2. Evidently the strip of strengthening material h' may be glued to the inner face of the leather cover and turned over with the edges d'' and glued to the tongue c'. The different layers of material are shown of exaggerated thickness in Fig. 3 for the sake of clearness of illustration.

70 My invention is not confined to all of the details of construction above described, and the construction may be modified without departing from my invention. If heavy leather is used, some of the filling material and the muslin tip may be omitted, and the particular kind of material used may be greatly varied. The edges of leather which are turned over 75 upon the filling are usually shaved thin, so as to give a neat finish. The tuck is inserted in the usual slit m or under a strap on the pocket for holding the flap in place.

The tuck D, applied as above described, is 80 durably secured to the flap without stitching, is effective in use, and neat in appearance.

Having thus described my invention, what I claim, and desire to secure by Letters Patent, is—

90 1. In a pocket-book, or the like, a flap having a lining or interior portion provided with a tongue, and a tuck having a rearwardly-ex-

tending thumb-piece, the forward portion of said tuck being secured by an adhesive to said tongue, substantially as described.

2. In a pocket-book, or the like, a flap having a projecting tongue and a tuck applied at its front portion to said tongue, with its edge turned over and secured by an adhesive thereto, and having a rearwardly-projecting thumb-piece above the flap, substantially as described.
- 10 3. In a pocket-book, a flap having a tongue and a tuck having the edges of its front por-

tion and a reinforcing-strip turned over and secured by an adhesive on said tongue and flap, and having a thumb-piece extending rearward above the flap, substantially as described. 15

In testimony whereof I have signed my name to this specification in the presence of two subscribing witnesses.

HERMAN BRUEGER.
